CLAIM

I claim the ornamental design for a laser marking apparatus, as shown and described.

DESCRIPTION

FIG. 1 is a front view of a laser marking apparatus of the present invention;

FIG. 2 is a rear view of the laser marking apparatus;

FIG. 3 is a left side view of the laser marking apparatus;

FIG. 4 is a right side view of the laser marking apparatus;

FIG. 5 is a top view of the laser marking apparatus;

and,

FIG. 6 is a bottom side view of the laser marking apparatus;

and,

FIG. 7 is a perspective view of the laser marking apparatus.

1 Claim, 7 Drawing SheetsFIG. 1

FIG. 2

FIG. 3

FIG. 4

FIG. 5

FIG. 6
